WEB CUTTING APPARATUS

Edwin M. Kwitek, Green Bay, Wis., assignor to Paper Converting Machine Co., Inc., Green Bay, Wis., a corporation of Wisconsin

Application May 16, 1957, Serial No. 659,511

9 Claims. (Cl. 164—68)

This invention relates to web cutting apparatus, and is particularly useful in the perforating, cutting, or scoring or weakening along transverse lines of paper webs of the tissue paper type, such as facial tissue and toweling materials. The invention is applicable to kraft paper, textiles, and other webs.

In paper winding machines, and particularly in machines handling thin tissue paper such as facial tissue, toilet paper tissue, etc., a problem has long existed with respect to the transverse cutting or weakening of the paper because the thin paper web tears readily, and because of this, webs of limited width have to be employed and the speed of operation and production substantially curtailed. The weakening or scoring of the web transversely of the web is to provide, after slitting and in the finished web product, lines along which the web can be readily divided. As stated, the weakness of the paper tissue makes such cutting, weakening or scoring operation extremely difficult, and the machines today employed can handle commercially only webs of limited width. If apparatus could be provided which would allow rolls of paper of much greater width to be treated in the machine, production could be greatly increased and the cost of the paper-winding operation substantially reduced.

I have discovered mechanism which effectively cuts, perforates or weakens the paper web transversely of the web while at the same time applying the weakening or perforating operation at shortened intervals transversely of the web so that a lessening of tension upon the paper is produced and paper webs of greatly increased width can be effectively handled in the machine at high speed. This result is achieved by cutting the web in restricted areas progressively across the web rather than cutting the web all the way across in one machine step, with the result that a minimum of strain or stress upon the paper web is imposed during the cutting operation and an extremely wide web can be fed from the roll through the machine to give an even and clean-cut perforated line across the web.

An object of the present invention is to overcome the difficulties referred to above and to achieve the new results described. A further object is to provide a weakening or perforating apparatus which brings about the cutting, perforating or weakening at isolated points transversely of the web as the web is moving forward, so that a minimum of stress is applied to the web at any single instant. A still further object is to provide a sheercut mechanism in which a paper web is perforated, etc. transversely of the web, the perforations being accomplished in sequence across the web as the web advances in the machine. Yet a further object is to provide mechanism of unique and sturdy character which remains effective in the sheercut perforating, etc. of sheets after long use, while at the same time permitting rapid operation of the perforating mechanism. Other specific objects and advantages will appear as the specification proceeds.

2

The invention is shown, in an illustrative embodiment, by the accompanying drawings, in which—

Figure 1 is a broken diagrammatic showing of paper-winding apparatus employed in connection with my invention; Fig. 2, a top plan view of a knife-holder block which may be used in the practice of my invention; Fig. 3, a side elevation of the structure shown in Fig. 2; Fig. 4, a diagrammatic showing illustrating the action of the blades and knives employed in the practice of my invention; Fig. 5, a diagrammatic view showing a blade cutting edge in shearing relation to a stationary knife or line of cut; Fig. 6, an enlarged sectional view showing the blades and knives in the cutting or perforating step; Fig. 7, a detail sectional view showing the means employed for securing the blades in position upon the perforating or cutting roll; Fig. 8, an enlarged sectional view, the section being taken as indicated at line 8—8 of Fig. 6; Fig. 9, a detail sectional view, the section being taken as indicated at line 9—9 of Fig. 3; Fig. 10, a broken detail view showing the suspension of the cutting or perforating roll and the means for driving the same and Fig. 11, an enlarged broken sectional detail view showing the cutting blades just before engagement.

In view of the fact that most of the parts of a web-winding machine are old in the art, it is believed unnecessary to describe such parts in detail, and it should be sufficient to refer to them in a general way by reference to the diagrammatic showing in Fig. 1. By way of illustration, the cutting or web-weakening or perforating roll will be described herein as a "perforating roll," it being understood that this structure is merely illustrative of other forms of cutting, weakening, scoring, etc. mechanism.

In Fig. 1, 10 designates a paper web which leads from any suitable source. The invention herein may be employed on a rewinder or upon any form of mechanism. The web 10 passes over rolls 11, 12 and 13, as shown in Fig. 1, and thence over a perforating roll 14 which is equipped with structures embodying my invention. Cooperating with the perforating roll 14, are knife-holders 15 equipped with knives 16. The holders 15 are carried by a block member 15a. The knives 16 are in a spiral arrangement so that the blades of the perforating roll 14 cooperate with the spirally-arranged knives 16 of the block 15a in forming perforations successively across the web as the web moves from the first of the spirally-arranged knives 16 in the block 15a to the last of the knives in the block 15a. After perforation, the web 10 passes over the intermediate roll 17, the slitting roll 18 cooperating with the slitter 19, and thence over the bedroll 20 to the turret 21 onto which the paper is wound upon cores in a well-known manner. The rotatable mandrel turret 21, bedroll construction, and other mechanism herein are described in greater detail in the G. M. Kwitek Patent No. 2,512,900.

In the specific illustration given, the perforating roll is driven by the drive gear 22 through an intermediate gear 23 meshing with the perforating roll gear 14a and the slitter 19 is driven through the gear 24 meshing with the drive gear 25. Since such mechanism is well known, a further detailed description herein is believed unnecessary.

In the practice of my invention, I provide the perforating roll 14 with a transverse series of blades 26, as illustrated diagrammatically in Fig. 4, and the blades, thus supported in a line longitudinally of the roll, are successively brought into engagement with sectional knives 16 carried by a stationary knife-supporting block 15a. With this structure, as illustrated in Fig. 4, the thin tissue is carried over the roll 14 and between the notched blades 26 and the sectional knives 16 to bring about progressive perforating of the paper as the paper is advanced

over the roll. In other words, viewing the operation from Fig. 4, there is first a perforating of the paper film at the right-hand side of the roll 14, and then, as the web is advanced, the remaining portion of the web is successively perforated, the perforating action occurring incrementally as the paper is carried forwardly until the final perforation occurs between the blade and the segmental knife at the left-hand side of Fig. 4. The resulting perforation is, however, a true transverse perforation of the web and at right angles to the edge of the web.

In connection with Fig. 4, it will be understood that the segmental knives are supported on a member not shown in the figure, namely, by the stationary block 15a. For the purpose of illustration, however, it is believed that the diagrammatic showing in Fig. 4 indicates how the separate blades cooperate with the separate sectional knives as the paper is advanced over the roll 14 so that at no one time is the entire web subjected to a perforating or weakening action, but, instead, small portions only of the web are subjected to the perforating stress.

The perforating roll 14 is shown in greater detail in Figs. 5, 6 and 7. The roll 14, which is rotatively mounted for coaction with the knife-supporting block 15a, is provided with five spaced blades 26. Each blade is formed of hardened steel and is preferably resilient and is so supported as to enable the blade to flex during action. I prefer to employ a high carbon chrome steel (62-65 Rockwell C scale), having the grain of the steel running transversely of its width and having the edges of the blade notched on both sides, as indicated by the numeral 27. Such a blade is shown in detail in Fig. 7. By way of example, when such a blade has a thickness of .032", it is found that effective flexing occurs while at the same time excellent perforation is brought about. Such a blade provides four cutting edges and may be reversed in position upon the roll 14 so as to be effective in perforating the paper over a long period of time. The blade may be made thicker or thinner, depending upon the materials being cut, the diameter of the roll, and other conditions.

As indicated best in Fig. 7, the roll 14 is cut away to provide a notch or recess 28 providing a bearing surface 29 for the blade 26, and below the bearing surface 29 there is a further recess 30, relieving the forward edge of the blade 26 for flexing. The blade 26 is clamped upon the surface 29 by the clamping member 31, and I prefer to employ a resilient strip 32, formed of rubber, or the like, between the clamp 31 and the blade. The roll 14 is provided with a plurality of tapped recesses 33 for receiving the screws 34, and the screws passing through the openings 35 of the clamp shoe 31 are effective in securing each of the blades 26 in positions extending across the length of the roll 14. While the position of the blade may be varied, I have found that very effective operation has been obtained where the blade protrudes .060" beyond the periphery of the roll, but it will be understood that the positioning of the blade may be varied substantially depending upon the type or character of paper being perforated, etc.

While, in the illustration given, I have shown five longitudinal series of blades extending across the roll 14, it will be understood that the number of blades can be increased or diminished, depending upon the arrangement of the knives, the material being perforated, etc.

The stationary knives 16 and the knife-holders 15 will now be described in connection with the holder block 15a. In Figs. 2 and 3 are shown views of a metal casting which is employed to support the knives or blades 16 and the holders therefor in different angular positions so that such knives will occupy a position very much as illustrated in the diagonal sketch shown in Fig. 4. The casting 15a provides successive faces 36 which are turned in planes varying slightly, as illustrated in Fig. 2, so as to bring the blades to be supported thereby into

a spiral arrangement, as indicated in the diagrammatic view of Fig. 4. To each of the faces 36 is secured a knife-holder 15, as illustrated best in Fig. 6, and the knife-holder is preferably enlarged or slotted, as indicated by dotted lines 37, to adjustably receive the spring-urged bolts 38. A pair of bolts 38 extend through slots 37 in each knife-holder and anchor the knife-holder adjustably in position. There are two bolts for each knife-holder 15, and the nuts 39 thereon compress the springs 40 to hold the knife-holder effectively in position while at the same time permitting adjustment of the knife-holder through the thumbscrew 41. The knife 16 is held in position by a shoe 42, which in turn may be held in position by a setscrew 43. With the structure shown, the springs 40 bearing against each knife-holder 15 are effective in holding the knife-holder and the knife 16 carried thereby in a selected position while at the same time, however, permitting the knife-holder to be adjusted outwardly upon application of pressure from the thumbscrew 41 shown above each of the knife-holders.

The knife-holders 15, as shown best in Fig. 9, support a series of knives or blades 16 in a spiral arrangement corresponding to the showing in Fig. 4, so that as each blade 26 of the perforating roll 14 moves in a counterclockwise direction, each of the blades 26 in longitudinal alignment on roll 14 engages a corresponding knife 16 carried by the knife-holders 15 in a successive movement during the arc of travel shown between the first knife-holder 15 at the right of Fig. 9 and the last knife-holder indicated at the left-hand side of Fig. 9. Not only is the row of blades 16, as shown in Fig. 4, at an angle, but each individual blade 16 is at an angle so that the cutting at any instant is at a single point of contact. This is illustrated in Fig. 5.

It will be observed that the blades of the perforating roll 14 are matched in length with the knives of the block member 15a so that one blade of the roll 14 will engage an oppositely-disposed knife of the block 15a, this engagement being progressive, as indicated in the diagrammatic showing of Fig. 4, as the perforating roll rotates.

Operation

In the operation of the apparatus, the paper web 10 is advanced, as indicated by the arrows in Fig. 1, over the rolls 11, 12 and 13, and thence over the perforating roll 14. As the web is carried forwardly in the direction of the arrow on roll 14, the blade 26 at one end of the roll 14 engages the first knife shown above the center of the roll 14, and then successively the blades 26 running longitudinally of roll 14, engage the spirally-arranged individual knives 16 of the block 15a so as to perforate the web transversely, the perforations, however, being produced sequentially from one edge of the web to the other. The perforated web 10 then leaves the roll 14, is slit upon roll 18, and the slit strips are wound each upon its separate core upon the mandrel turret 21. In the above operation, the severed portion of the web is free to move forwardly as the unsevered portion is meeting the contacting knife portions.

When adjustment is desired, the thumbscrews 41 may be turned to project the segmental knives 16 outwardly while also, when desired, the notched blades 26 may be reversed in position or turned over to present new severing edges.

In the foregoing operation, it is found that high speeds can be obtained because the contact between the metal cutting parts is only for an instant and between separate members, while also because of the sequential perforating action of each longitudinal row of blades, the fragile tissue web is subjected to a minimum of tension, and tearing does not occur. Webs of a width far greater than those heretofore transversely scored or weakened may be effectively perforated by the present machine.

While I have shown a specific structure in which perforation of the web is accomplished, it will be understood

that the invention herein may be employed with other means for transverse cutting, weakening, scoring, etc., of web material. The mechanism described gives a clean-cut perforating action, and because of the sequential action described, there is no danger of overheating of metal parts and the apparatus can be used over long periods of high production without requiring change.

By the term "cutting" as employed in the claims, it is intended to include partial cutting, as by perforations, scoring, or other transverse breaking of the web material.

As indicated in Fig. 10, the perforating roll 14 is suspended from the support 15a and is driven through the gear 14a. The frame 15a supports the knives or blades 16, as heretofore described in detail. If desired, the ribbing structure shown in Figs. 6 and 9 may be omitted and a simple knife-supporting bar employed for holding the knives or blades 16 in position.

If desired, the frame 15a may be hinged at one end so that the same may be lifted to permit ready threading of the web between the perforating roll and the stationary knife structure. Further, if desired, the felt members 32 which support the blades 26 upon the perforating roll 14 may be saturated with oil so as to prevent the formation of alum deposits, etc. on the knives and prolong the knife life.

With the structure shown, no wrench or tool is necessary for the adjustment of the machine and thus there is no danger of a wrench dropping into the machine. The perforation or cutting action is positive, and the machine avoids the formation of paper dust fragments which are found in prior perforating or cutting machines. In the handling of highly creped paper, it is hard for the knife edges to enter, and the bond is weakened so that it is difficult to rewind. With the present structure, sharp cutting or perforating action takes place so that strong bonds are maintained and the paper can be readily rewound.

Threading of the web through the machine and between the roll and fixed cutters is accomplished readily and, as stated above, if desired, the fixed frame 15a can be hinged for raising or lowering to facilitate such threading. In the operation of the machine, there is substantially no shock and very little pressure at any particular point. The cutting action as it moves transversely of the machine along the web is concentrated at a particular point not only on the cutter as a whole, but upon each individual blade or knife so that there is a minimum of strain upon the web and a progressive cutting is carried on across the roll, the cutting members providing a clearance between them as the web advances so that there is no obstruction to the free flow of the web over the perforating roll.

The resilient strip 32 has been found very effective in permitting a yielding of the blade edge in operation for effective cutting without bending or breakage of the blade. In the specific machine illustrated, the rubber pad is $\frac{1}{16}$ of an inch in thickness, but it will be understood that other thicknesses may be employed depending upon the material being cut, and also other yielding and padding material may be employed. As shown more clearly in Figs. 1, 6 and 7, the resilient blade 26 extends outwardly from the cutter roll at an inclination with respect to a radial line drawn from the center to the cutting edge thereof and forms with said radius or radial line an acute angle. The inclined blade 26 thus lies under the web 10 which is fed over the surface of the cutter roll, flexing inwardly when engaging the rigidly clamped blade 16. Also, as shown in the drawing and more clearly in Figs. 6 and 11, the stationary blade 16 has a cutting edge defined by angularly related surfaces, in the illustration given a right angle. The cutting edge-defining surface first in the path of the resilient blade 26 is angularly inclined relative to the radial line drawn to the stationary blade cutting edge and forms an obtuse angle therewith. In the illustration given, the other cutting edge-defining surface also forms an obtuse angle with the radial line.

As illustrated best in Figs. 6 and 9 and as hereinbefore described, each resilient roll blade, having one longitudinal edge clamped firmly upon the roll, provides a protruding free flexing cutting edge and the roll is recessed about such protruding blade portion to relieve the cutting edge for flexing during the action. The corresponding oppositely-disposed knife blade is supported by the block adjacent the roll to bring the knife edge sufficiently within the path of travel of the roll blade, as the roll rotates, to bring about engagement between the blades and the resilient roll blade edge in such contact flexes and yields. The engagement of the oppositely-disposed blades, by reason of their angular relation to each other, is at any instant at a single point of contact.

While, in the foregoing specification, I have set forth a specific structure in considerable detail for the purpose of illustrating an embodiment of the invention, it will be understood that such details of structure may be varied widely by those skilled in the art without departing from the spirit of my invention.

I claim:

1. In web cutting apparatus, a frame, a cutting roll rotatably mounted in said frame, means for rotating said roll, a resilient cutting blade rigidly supported upon said roll at a spaced distance from its cutting edge to provide a free flexing cutting edge, said blade being inclined with respect to a radial line drawn from the cutting edge to the roll center and forming with said line an acute angle, means for feeding the web over said roll and over said blade for travel upon said roll, a blade-supporting block adjacent said cutting roll, a stationary cutting blade rigidly supported in said block and presenting a cutting edge for coaction with said first-mentioned cutting blade, said blades having their cutting edges at an angle to each other and said stationary blade having its cutting edge radially inward of the path of travel of the cutting edge of the rotating blade, the cutting edge of the stationary blade being defined by angularly related surfaces, the cutting edge-defining surface first in the path of said rotating blade being angularly inclined relative to a radial line drawn to the stationary blade-cutting edge, whereby said blade edges engage during the rotation of said roll and said free flexing cutting edge yields during engagement with said rigidly mounted stationary blade.

2. The structure of claim 1, in which at least one of said blades is notched so as to perforate said web.

3. The structure of claim 1, in which said second-mentioned blade is rigidly clamped upon said block substantially throughout its length and in which the free flexing portion of said resilient blade extends within a recess of said roll.

4. In web cutting apparatus, a frame, a cutting roll mounted for rotation in said frame, means for rotating said roll, means for feeding a web on said roll for travel thereon, said roll having a plurality of circumferentially spaced recesses therein and a rigid bearing surface within each recess, a resilient blade rigidly supported upon the bearing surface in each recess and having inclined outwardly-extending free portions provided with a cutting edge, said roll being provided with a further recess about each outwardly-extending free blade portion for relieving the same for flexing, the inclination of each blade being such that it forms with a radial line drawn from its cutting edge to the roll center an acute angle, a blade-supporting block adjacent said roll adapted to support a blade for contact with the blades on said rotating roll,

70 a stationary blade rigidly supported on said block and having its cutting edge radially inward of the path of travel of the cutting edges of the roll blades, said stationary blade being arranged with its cutting edge at an angle to the cutting edge of each roll blade as the edges 75 of said blades are brought into engagement during the

rotation of said roll in the cutting operation, the said resilient blade edge yielding during said engagement.

5. The structure of claim 4, in which said block supports a plurality of stationary blades for engagement with the said resilient blades.

6. The structure of claim 4, in which a row of resilient blades is mounted within each recess and in which a row of stationary blades is supported upon said block for engagement with said resilient blades.

7. In web cutting apparatus, a frame, a cutting roll mounted for rotation in said frame, means for rotating said roll, means for feeding a web on said roll for travel thereon, said roll having a recess therein and a rigid bearing surface within said recess, a resilient blade rigidly supported upon said bearing surface within said recess and having an unsupported, outwardly-extending cutting edge portion, said roll being provided with a further recess about said outwardly-extending free edge for relieving said edge for flexing, a blade-supporting block adjacent said roll, and a row of stationary blades rigidly supported throughout their length on said block adjacent their cutting edges and having their cutting edges radially inward of the path of travel of the cutting edge of the roll blade and arranged at an angle to the cutting edge of the roll blade to bring the edges of said roll and stationary blades into engagement during the rotation of said roll, the said resilient blade edge yielding during said engagement, the roll blade being inclined relative to a radial line from the roll center through the roll blade cutting edge and each of said stationary blades having cutting edges defined by angularly-related surfaces, both of said surfaces forming obtuse angles with a radial line drawn to its cutting edge.

8. In web-perforating apparatus, a frame, a cutting roll mounted for rotation in said frame, means for rotating said roll, means for feeding a web to said roll for partial wrapping engagement therewith, a plurality of resilient blades mounted upon said roll in circumferentially spaced-apart relation and extending longitudinally thereof, said blades being rigidly supported along their inner edge portions on said roll and providing outwardly-extending free cutting edge portions protruding from said roll, said resilient blades being inclined in a nonradial direction, a blade-supporting block adjacent said roll, a plurality of stationary blades rigidly supported upon said block and arranged at an angle to the blades on said roll to provide progressive point contact between said roll blades and said block blades, said block blades having their cutting edges radially inward of the path of travel of the cutting edges of said roll blades, whereby said roll blades yield inwardly during engagement in the cutting operation, each of said stationary blades having cutting edges defined by angularly related surfaces, each

of said surfaces being inclined in a nonradial direction, at least one of the pluralities of blades being notched to perforate said web.

9. In web cutting apparatus, a frame, a cutting roll mounted for rotation in said frame, means for rotating said roll, means for feeding a web on said roll for travel thereon, said roll having a plurality of circumferentially spaced, longitudinally extending recesses therein, a resilient blade rigidly supported in each recess and having inclined outwardly extending free portions provided with a cutting edge, the said resilient blade being rigidly supported in each recess along the edge thereof opposite its cutting edge, said roll being provided with a further recess about each outwardly extending free blade portion for relieving the same for flexing, the inclination of each blade being such that it forms an acute angle with a radial line drawn from its cutting edge to the roll center, a knife holder adjacent said roll adapted to support a blade for contact with the blades on said rotating roll, a row of stationary blades rigidly supported on said knife holder and having their cutting edges radially inward of the path of travel of the cutting edges of the roll blades, said knife holder being mounted for moving said stationary blades toward and away from said roll blades, said stationary blades being arranged with their cutting edges at an angle to the cutting edge of each roll blade as the edges of said blades are brought into engagement during the rotation of said roll in the cutting operation, the said resilient blade edge yielding during said engagement.
